UNITED STATES PATENT OFFICE.

HENRY A. SCHAEFER, OF ROCHESTER, NEW YORK, ASSIGNOR TO SCHAEFER & SCHLEGEL, OF SAME PLACE.

DESIGN FOR A SKIRT-PROTECTOR.

SPECIFICATION forming part of Design No. 29,101, dated July 26, 1898.

Application filed July 2, 1898. Serial No. 685,057. Term of patent 14 years.

To all whom it may concern:

Be it known that I, HENRY A. SCHAEFER, a citizen of the United States, residing at Rochester, Monroe county, New York, have invented and produced a new and original Design for a Skirt-Protector, of which the following is a specification, reference being had to the accompanying drawing, forming a part thereof.

10 My design is shown in the accompanying drawing, which represents a face view, on an enlarged scale, of a piece of skirt-protector.

15 The leading feature of my design is a skirt-protector having the body of fabric and a fringe or brush at the edge, the body being ornamented by the successive series of diagonally-arranged spots contrasting in appearance therewith by reason of their color or surface finish, or both.

In the drawing, 1 indicates the body of the 20 protector, and 2 the brush at the edge. The upper edge 3 and the major portion of the body have approximately the same rough-finished appearance, and just below the upper edge and above the fringe are the small headings 4 and 5, respectively, and the space between these headings is ornamented by successive series of diagonally-arranged spots 6, which contrast in appearance, as shown, with the field on which they are located by reason 30 of their color or finish, or both.

I claim—

The design for a skirt-protector, substantially as shown and described.

HENRY A. SCHAEFER.
